(57) **CLAIM**

The ornamental design for an arm rest apparatus, as shown and described.

DESCRIPTION

FIG. 1 is a front view of an arm rest apparatus of our new design;

FIG. 2 is a rear view of the arm rest apparatus shown in FIG. 1;

FIG. 3 is a top view of the arm rest apparatus shown in FIG. 1;

FIG. 4 is a bottom view of the arm rest apparatus shown in FIG. 1;

FIG. 5 is a left side view of the arm rest apparatus shown in FIG. 1;

FIG. 6 is a right side view of the arm rest apparatus shown in FIG. 1;

FIG. 7 is a perspective view of the arm rest apparatus shown in FIG. 1;

FIG. 8 is a view for a reference, which shows a position relationship of the arm rest apparatus with respect to an arm; FIG. 9 is a view for a reference, which shows another position relationship of the arm rest apparatus with respect to an arm; and,

FIG. 10 is a view for a reference, which shows a using state of the arm rest apparatus.

The broken lines are included for the purpose of illustrating environment and unclaimed subject matter and form no part of the claimed design.

1 Claim, 9 Drawing Sheets
